UNITED STATES PATENT OFFICE

EDMUND GILBERT LODGE, OF PHILADELPHIA, PENNSYLVANIA, ASSIGNOR TO AT-
WATER KENT MANUFACTURING COMPANY, OF PHILADELPHIA, PENNSYLVANIA,
A CORPORATION OF PENNSYLVANIA

ELECTRICAL CONTACT DEVICE

Application filed March 8, 1929. Serial No. 345,274.

My invention relates to volume control rheostats for radio receiving apparatus, in which noise-producing imperfect contact is prevented by recourse to structure of the character hereinafter described, including a sliding contact member adapted to rock or oscillate about its axis transverse to its direction of travel to maintain it in multi-point contact with a resistance element.

18 My invention resides in movable contact structure comprising a resilient contact member pivotally supported at one end, and in engagement with a yielding abutment adjacent its free or contacting end; more particularly the yielding abutment comprises a resilient supporting member, fixed at one end, the free end of which comprises a fulcrum adapted to engage and bias the resilient contact arm more firmly into engagement with 25 its cooperating contact; and more particularly the contact and resilient supporting members are mounted coaxially and in superposed relation with respect to each other.

25 My invention further resides in movable contact structure of the character above described wherein the yielding abutment engages the contact member at a point on its longitudinal axis, whereby oscillation of the contact member with respect to its longitudinal axis is permitted; more particularly the cooperating or stationary element with which the movable contact member coacts comprises a curvilinear resistance element, specifically a coiled resistance wire, upon the 30 surface of which rides the movable contact with minimum friction; more particularly the resilient supporting member has less flexibility than the contact member whereby firm 35 and even pressure is applied through the said fulcrum to maintain the coacting contacting portions in continuous and smooth engagement; and more particularly the pressure applied to the contacting portion through 40 said fulcrum is at a point radially offset with

respect to the point of bearing contact pressure.

My invention further resides in apparatus of the character hereinafter described and claimed.

For an illustration of some of the forms my invention may take, reference is had to the accompanying drawing in which:

Fig. 1 is a side view, partly in section, of a variable contact device.

Fig. 2 is an elevational view of the device illustrated in Fig. 1.

Fig. 3 is a detailed lower plan view of contact structure.

Fig. 4 is a detailed upper plan view of the contact structure shown in Fig. 3.

Fig. 5 is a side view of the structure illustrated in Figs. 3 and 4.

Fig. 6 is a detailed view of modified contact structure prior to assembly.

Fig. 7 is an endwise view of contact structure looking towards the free end thereof.

Fig. 8 is a partial view illustrating the contact structure of Figs. 3 and 4 in engagement with a resistance element.

Fig. 9 is a lower plan view of another modified form of contact structure.

Fig. 10 is a side view of the structure shown in Fig. 9.

Fig. 11 is a diagrammatical illustration of radio receiving circuits.

Referring to Figs. 1 and 2, a casing M of molded insulating material of suitable characteristics comprises a cup-like member having rotatably and centrally mounted in a wall 40 thereof the shaft J. An operating knob J1 is secured to one end of shaft J and a boss or hub H is secured to the other end thereof, as by a set screw H1, or equivalent. A pair of resilient superimposed leaf members A and S comprising rotatable contact structure are secured to hub H by an upset portion Q in a manner presently described. The resilient leaf member S engages the upper surface of a resistance R and is in turn engaged 45

by an abutment or fulcrum P carried by the other leaf member A. The resistance element or resistor R comprises a resistance wire wound in any suitable manner upon a curved insulating strip O secured to the casing M at its opposite ends by the binding posts or screws O1 and O2. Hub H, to which the contact arm S is electrically connected, is frictionally engaged by a resilient positioning and conducting member W, through which shaft J extends, and which is adapted to maintain shaft J in operative position wherein the knob J1 serves as a stop member, and also to provide electrical contact between arm S and a binding post O3 which secures member W to the casing.

Referring more particularly to Figs. 3 to 5 inclusive, hub H comprises an annular portion Q over which the leaf spring-like members S and A are placed in superimposed position, after which portion Q is upset to clamp or rivet the spring members firmly to hub H. The lower leaf member S, Fig. 3, comprises a tapering portion having a plane or flat contacting portion or shoe K at its outer end and is notched or otherwise reduced in width adjacent its free end to form a comparatively thin neck portion N which is less resistant to torsional stress than other portions of the member. In other words, contact shoe K is permitted to oscillate rather freely about its longitudinal axis in response to comparatively small torsional moments. Member S is furthermore preferably slotted 35 at S1, thereby insuring comparative lightness and flexibility of the contact arm.

As will be noted in Fig. 4, the upper or overlying member A, being slotted only at A1, is less flexible than contact arm S. Adjacent the outer or free end of member A are abutments P and P' disposed substantially along the longitudinal axis of A and extending towards the upper surface of contact shoe K. The resilient leaf members A and S normally tend to assume the curvilinear shapes illustrated in Fig. 5.

In Fig. 6 there is illustrated a leaf member A having a single abutment P at its free end such as is shown in Fig. 1. The leaf members A and S are furthermore shown prior to assembly with respect to hub H, and upon which they may be firmly united by the riveting portion Q.

The contact structure previously described is particularly adapted to engage, as by a sliding action, the surface of a resistance element, particularly of the type comprising a coiled resistance wire whose edge or contacting surface is apt to have slight or minor irregularities, but which nevertheless are sufficient to seriously interfere with smooth and even mechanical operation of an ordinary contacting arm therewith. In other words, an ordinary contact arm riding upon such a surface often produces a scraping noise, particularly when

the contact arm and resistance are comprised within radio receiving circuits, as in the volume control circuit, due to the fact that the edges of the contact do not ride evenly over the irregularities of the resistance element. Furthermore, the area of contact, and therefore the contact pressure, is apt to vary widely due to the fact that the plane of the contact, is not always parallel with the surface with which it is in engagement, but on the contrary is often in single point instead of multi-point contact therewith.

Referring to Fig. 8, the contact arm structure is shown in operative relation with the resistance R. The contact arm S, it will be noted, is flexed in such manner that contact shoe K is in substantially a horizontal plane by reason of the engaging abutments P and P1 on the less resilient leaf member A. Accordingly, it will be observed that in addition to the pressure exerted upon the contact shoe K by the resilient arm S there will be an even greater and more positive pressure exerted by the superimposed member A through the abutments P and P1. If the contact arm S were solely relied upon to provide proper contacting pressure, the comparative lightness and flexibility of this member would cause contact shoe K to contact unevenly and unsteadily with the resistance R. If on the other hand a contact arm having the characteristics of member A were solely relied upon to maintain proper contacting engagement with the resistance element, the edges of the member, due to the greater bearing pressure exerted by the more rigid arm, would tend to dig in or catch along the irregularities of the resistance element, and so result in noisy and unsatisfactory operation.

By providing a comparatively flexible and resilient contact arm and a more rigid or supporting arm therefor, about whose longitudinal axis the contact arm may oscillate, sufficient bearing pressure is maintained at the contacting surfaces while at the same time reducing or practically eliminating the dragging action of the contact portion, and the consequent increased friction and scraping sound due thereto. To this end, the abutment or abutments engaging contact shoe K are disposed substantially along the longitudinal axis of arm S, thereby acting as a fulcrum or pivot point about which contact shoe K may oscillate or rock about its longitudinal axis to conform to the irregularities of the resistance element. Such oscillatory movement, permitting the plane of the contacting portion to coincide or engage in multi-point contact with its coating surface, is furthermore facilitated by the comparatively flexible necked-in portion N of the contact arm whereby the torsional moment required to oscillate the contact shoe may be comparatively small. Accordingly, as shaft J is rotated the contact shoe K will ride evenly over

the resistance element R, rocking with respect to its longitudinal axis about the abutment or abutments at the end of member A as the surface of the resistance element varies in contour.

The radial position of the abutment P is preferably beyond the bearing contact surface and engages the extreme outer end of contact shoe K to maintain it in firm and continuous contact with the resistance element. Or the abutment P may be directly above the bearing contact surface, depending on the curvature of the movable contact member. Accordingly there is a tendency for the movable contact shoe to ride tangentially along the top or the top-outer edge of the resistor, thereby obviating any "digging in" action of the edges of the movable contact. If abutment P were disposed on the opposite side of the point of contact, other factors being the same, contact shoe K would tend to tilt inwardly and away from its normal plane because of the relative weakness of neck N. This would be an undesirable feature since it is essential for smooth and quiet operation that the plane of the contacting portion be substantially parallel or coincide with the plane defined by the circular contact edge of the resistor. In other words, the contact shoe should not ride along the top-³⁰ inner edge of the resistor for there would then be a tendency for the edges of the shoe to "dig in" and produce a scratching sound. The above described feature is clearly illustrated in both Figs. 1 and 8, the additional abutment P₁, Fig. 8, being provided to allow for irregularities in the curvature of the resistance element with respect to the axis at J. The abutment, instead of the individual depressed portions P and P₁, may evidently comprise a continuous ridge or V-punching in the supporting leaf A, the ridge extending substantially co-incident with the longitudinal axis of contact arm S, and for such length as is required by the variation in radius of curvature of the resistance element. Accordingly, the abutment or member A serves not only to properly position the longitudinal axis of the contact shoe K, but to act as a fulcrum or pivot about which the contact shoe may oscillate or rock to maintain even multi-point contact with the resistor.

Figs. 9 and 10 illustrate a further modification of my contact arm wherein but a single leaf member is employed. Boss H has riveted thereto at Q in the manner described above a tapering resilient member A, from which a tongue-like portion is stamped at Y. The stamped out portion, bent in reversed direction at its narrowest portion U, comprises a contact shoe K₁ carried by a comparatively narrow flexible strip N₁ secured at U to leaf member A. As in the previous instances, the contact shoe K₁ is carried by a comparatively flexible or resilient member

having small resistance to torsional stress, and is adapted to be urged when in operative position, firmly into engagement with its coacting surface immediately underneath the shoe by the more rigid supporting arm through the abutment P. When assembled in the manner illustrated in Fig. 1, the abutment P extends radially beyond the bearing contact surface and serves to maintain the plane of contact shoe K₁ substantially parallel to the plane of the coacting contact edge of the resistor. As in the previous instances, the abutment or fulcrum P is disposed on the longitudinal axis of both member A and the contacting shoe K₁, thereby permitting oscillatory movement of the contacting portion in the manner above described.

In Fig. 11 there is diagrammatically illustrated a portion of radio receiving circuits in which the above described variable contact device may be employed to effect volume control. A shielding conductor 1 is suitably connected to ground E. An antenna lead 3, disposed within the shielding conductor, is connected at one end to the antenna 6, and at the other end to a terminal of the resistance element R comprising volume control apparatus. A movable contact K coacting with the resistance element is electrically connected to the shielding conductor 1 and an artificial or set ground E'. The opposite terminals of resistance element R are connected by conductors 2 and 5, which are twisted with respect to each other, in the manner illustrated in a copending application Serial No. 299,933, filed August 16, 1928, by Dreyer, to an input coupling element L. Associated therewith is an electric valve V of the thermionic type having a grid g to which the coupling element is connected, a filament f heated by alternating current derived by means of transformer 7 from a suitable source of supply and a plate p connected in the output circuit of the valve comprising the primary of the step-up transformer T, whose secondary is associated in the usual manner with a tuning condenser C.

As the movable contact K is adjusted with respect to resistance R, appreciable variation in the contact pressure due to uneven or rough contacting engagement may produce a microphonic effect, which when amplified in the circuits of the radio receiving apparatus, produces objectionable noises similar to those produced by static in the sound reproducer. I have found that when my variable contact device is utilized in the volume control circuit, the action of contact K is practically noiseless due to the fact that even bearing pressure between the coacting elements is substantially maintained at all times. No appreciable microphonic effect is therefore produced, and the tone qualities of the radio receiving apparatus are not marred during adjustment of the volume control.

While the apparatus herein illustrated constitutes a preferred form of my invention, it shall be understood that a reasonable departure in construction may be made without departing from the spirit of my invention.

What I claim is:

1. In a volume control rheostat for radio receiving apparatus having a helix of resistance wire, means for preventing noise-producing imperfect contact with said helix comprising a resilient arm supported for movement along said helix and having an abutment adjacent the free end thereof, and a resilient contact member movable with said arm having a shoe pressed by said arm through said abutment into engagement simultaneously with a plurality of turns of said helix and having a reduced section intermediate said shoe and a support for said resilient contact member, said reduced section and said abutment permitting rocking of said contact shoe to ensure smoothly continuous variation of resistance during movement of said arm and to maintain direct wiping contact between a plurality of turns of said helix and said contact shoe. 80
2. In a volume control rheostat for radio receiving apparatus having a resistance element, means for preventing noise-producing imperfect contact thereat comprising a contact member having a shoe for engaging said element simultaneously at a plurality of points along the path of movement of said shoe, said contact member having a reduced section between said shoe and the support of said contact member less resistant to torsional stress than said shoe, and a member pressing said shoe into engagement with said resistance element through a fulcrum permitting rocking of said contact shoe facilitated by said reduced section to maintain multi-point direct wiping contact between said resistance element and said shoe. 85
3. In a volume control rheostat for radio receiving apparatus having a helix of resistance wire, means for preventing noise-producing imperfect contact with said helix comprising a contact member having a shoe for engaging said helix simultaneously at a plurality of turns thereof, and a reduced section intermediate said shoe and the support of said contact member, and a resilient arm overlying said contact member and engaging said shoe through an abutment forming a fulcrum permitting rocking of said contact shoe to maintain direct wiping contact between said helix and said contact shoe. 90
4. In a volume control rheostat for radio receiving apparatus having a resistance element, means for preventing noise-producing imperfect contact thereat comprising a resilient contact member rotatably supported at one end thereof, and having a contacting portion at its free end for engaging said resist- 105
5. In a volume control rheostat for radio receiving apparatus having a helix of resistance wire, means for preventing noise-producing imperfect contact with said helix comprising a resilient arm supported for movement along said helix and having an abutment adjacent the free end thereof, and a resilient contact member movable with said arm having a shoe pressed by said arm through said abutment into engagement simultaneously with a plurality of turns of said helix and having a reduced section intermediate said shoe and a support for said resilient contact member, said reduced section and said abutment permitting rocking of said contact shoe to ensure smoothly continuous variation of resistance during movement of said arm and to maintain direct wiping contact between a plurality of turns of said helix and said contact shoe. 110
6. In a volume control rheostat for radio receiving apparatus having a helix of resistance wire, means for preventing noise-producing imperfect contact with said helix comprising a contact member having a shoe for engaging said helix simultaneously at a plurality of turns thereof, and a reduced section intermediate said shoe and the support of said contact member, and a resilient arm overlying said contact member and engaging said shoe through an abutment forming a fulcrum permitting rocking of said contact shoe to maintain direct wiping contact between said helix and said contact shoe. 115
7. In a volume control rheostat for radio receiving apparatus having a resistance element, means for preventing noise-producing imperfect contact thereat comprising a resilient contact member rotatably supported at one end thereof, and having a contacting portion at its free end for engaging said resist- 120
8. In a volume control rheostat for radio receiving apparatus having a helix of resistance wire, means for preventing noise-producing imperfect contact with said helix comprising a contact member having a shoe for engaging said helix simultaneously at a plurality of turns thereof, and a reduced section intermediate said shoe and the support of said contact member, and a resilient arm overlying said contact member and engaging said shoe through an abutment forming a fulcrum permitting rocking of said contact shoe to maintain direct wiping contact between said helix and said contact shoe. 125
9. In a volume control rheostat for radio receiving apparatus having a helix of resistance wire, means for preventing noise-producing imperfect contact with said helix comprising a contact member having a shoe for engaging said helix simultaneously at a plurality of turns thereof, and a reduced section intermediate said shoe and the support of said contact member, and a resilient arm overlying said contact member and engaging said shoe through an abutment forming a fulcrum permitting rocking of said contact shoe to maintain direct wiping contact between said helix and said contact shoe. 130

ance element simultaneously at a plurality of points along the path of movement of said contacting portion to effect a direct wiping contact with said resistance element, and a member mounted coaxially with and in superposed relation to said contacting portion having a fulcrum engaging said contacting portion at a point radially beyond its contact with said resistance element. 70
